United States Patent Office

Des. 202,494

Patented Oct. 12, 1965

202,494

MATERIAL HANDLING VEHICLE

Glen W. Burgess, Battle Creek, Mich., assignor to Clark
Equipment Company, a corporation of Michigan

Filed July 6, 1964, Ser. No. 80,711

Term of patent 14 years

(Cl. D14—3)

FIG. 1

The dominant features of my design reside in the portion illustrated in solid lines.

I claim:

The ornamental design for a material handling vehicle, as shown and described.
